SEQUENTIAL CONTROL SYSTEM FOR SOOT BLOWERS

Curtis L. Howse, Spartanburg, S. C., assignor to
 Diamond Power Specialty Corporation, Detroit,
 Mich., a corporation of Michigan

Application April 21, 1949, Serial No. 88,854

29 Claims. (Cl. 60—97)

1

The present invention relates to systems and mechanisms for the control of fluid actuated apparatus, having particular utility in connection with the control of soot blowers and analogous cleaning devices of the type incorporating blowing elements for projecting a cleaning agent against surfaces or objects to be cleaned. Soot blower units, particularly as used for the cleaning of large boilers, are commonly arranged either to rotate or to rotate and move longitudinally, and the present system is adapted to control the time of blowing and all of the operative movements of a plurality of such movable soot blowers in such manner that the blowers may be made to function automatically, in predetermined sequence.

An important object of the present invention is to provide an improved control system of the indicated character which is adapted to regulate the action of a plurality of blower heads of different types and operating characteristics.

Another object is to provide such a control system which employs air as the actuating fluid for controlling the action of the soot blowers or other controlled elements, and which incorporates an improved and simplified master control mechanism adapted to be arranged at a control station remote from the controlled blowing devices, the master control mechanism permitting an operator to vary or interrupt the sequence of operations of the controlled devices at will, to change the operating cycle of the system.

Another object is to provide such a control system of greatly simplified character which requires only a single conduit from the control station to each controlled device.

Still another object is to provide an improved control system of the indicated character which is so arranged as to indicate at all times the blowing sequence or sequence of operation of the controlled devices, both while they are operating and after the operating cycle is concluded, at which latter time the system shows the operating sequence of the preceding cycle.

Another object of the invention is to provide such a system adapted to control a plurality of blowing units which differ from one another in construction, operating characteristics and in the blowing media employed as well as in blowing pressures. For example, the system may be used to control some blowers which utilize air as the cleaning agent and others which utilize steam, while the blowers utilizing air may operate at different pressures, and the duration of blowing and the pattern and nature of movement of mov-

2

able blowers incorporated in the system may vary widely.

A further object is to incorporate in such a system improved means for preventing the operation of blowers utilizing steam until condensate in the steam lines has had an opportunity to drain.

Other objects and advantages of the invention will become apparent upon consideration of the present disclosure in its entirety.

In the drawings:

Figure 1 is a schematic diagram of a control system incorporating principles of the present invention;

15 Figure 2 is a front elevational view of the control panel of a central control mechanism also incorporating features of the present invention;

Figure 3 is a horizontal sectional view taken 20 substantially on the line 3—3 of Figure 2 and looking in the direction of the arrows;

Figure 4 is a fragmentary rear elevational view taken as indicated by the arrow 4 of Figure 5;

25 Figure 5 is a side elevational view of the panel and associated mechanism, taken as indicated by the line and arrows 5—5 of Figure 2;

Figure 6 is an enlarged fragmentary elevational view of the portion enclosed within the dotted circle 6 of Figure 4;

30 Figure 7 is a fragmentary elevational view taken substantially as indicated by the line and arrows 7—7 of Figure 6;

Figure 8 is an enlarged fragmentary rear elevational view of the carrier assembly and associated parts for actuating the panel control valves;

Figure 9 is a sectional elevational view taken 35 substantially on the line 9—9 of Figure 8, and looking in the direction of the arrows;

Figure 10 is an enlarged fragmentary elevational view of the start-stop valve and associated parts;

40 Figure 11 is a sectional elevational view taken substantially on the line 11—11 of Figure 10, and looking in the direction of the arrows;

Figure 12 is a somewhat diagrammatic sectional plan view taken substantially on the line 12—12 of Figure 11, and looking in the direction of the arrows;

45 Figure 13 is a diagrammatic view of motor control valving means employed in connection with the control of certain rotary types of soot blowers adapted to be incorporated in a system arranged in accordance with the present invention, certain of the parts being shown out of

3

their operative positioning for clarity of diagrammatic depiction;

Figure 14 is a sectional elevational view, also diagrammatic in character, taken substantially on the line 14—14 of Figure 13 and looking in the direction of the arrows, but with the parts arranged in their proper operative positioning;

Figure 15 is a central vertical sectional view of a flow valve; and

Figure 16 is a bottom sectional plan view taken substantially on the line 16—16 of Figure 5, and looking in the direction of the arrows.

Referring now to the drawings, Figure 1 shows schematically the arrangement of the principal components of a system adapted to control the operation of a plurality of soot blowers of different types. The details of construction of the blower units themselves form no part of my present invention, but it is assumed for purposes of illustration that all of the blowers are of a movable type, either rotary, reciprocating or rotary and reciprocating, and as previously indicated various types may be incorporated in and controlled by the system. Suitable blowers are shown, for example, in Patents Nos. 1,899,733, 2,126,683, 1,644,286 and in De Mart patent application Serial No. 766,183 filed August 5, 1947. For purposes of the present disclosure, it will be assumed that each blower, regardless of type, is provided with a pressure-controlled driving motor which is air-operated, although it will be understood that other types of pressure-controlled driving motors might be used, as for example, electric motors with pressure switches.

The action of the entire system is supervised from a control station which may be, and normally is, located at a point remote from all of the blowers. The mechanism at the control station is mounted on a control panel 20 and supporting frame 22. The panel 20 is centrally provided with a vertical slot 24 behind and in alignment with which a carrier 26 is adapted to travel. A guiding rib portion 25 on the carrier projects slidably into the slot. A knob 28 attached to the rib 25 projects forwardly from the front face of the panel, while the block 26 travels behind the panel and is laterally slotted at 27A and slidably interfitted with a guide rail 27 supported behind the slot 24 by the frame 22. The rail 27 may be a relatively flat strip and positioned to serve as a baffle preventing vision through the slot, as best shown in Figure 3. The carrier block is normally urged upwardly by a counterweight 30 which also acts as a piston and which is vertically slideable in a cylinder 32 supported as by bracket means 34 behind the panel and in parallel relation to the slot 24. A flexible wire 35 is attached at one end to the block 26 and at the other end to the piston weight 30 and its intermediate portion is trained over a pulley 36 journaled in appropriate position near the top of the assembly as in the bracket means 38. The cylinder 32 may be substantially closed at one or both ends, only a predetermined orifice being left to control the rate of air flow, thereby forcing the piston and cylinder assembly to serve as a dashpot to control the rate of movement of the block 26.

The block 26 carries a transverse plate 40 to the outer vertical edges of which a pair of rearwardly extending hinge plates 42, 45 are pivoted for swinging movement about hinge pins 44, 47. A pair of headed screws 46, 48 project outwardly from opposite sides of the block through enlarged holes (undesignated) in the plates 42, 45. The holes are large enough so that the screws 75

4

do not interfere with swinging movement of the plates within their intended range, but the head of each screw limits outward movement of the plate through which it extends, and a compression spring 51, 52 on each screw beneath the plate urges the plate outwardly. Outward movement of the hinge plates is limited as by the abutment screws 46, 48 so that the plates are prevented from swinging outwardly away from one another beyond the approximate positioning shown in Figure 3 in which they are parallel to one another and perpendicular to the panel.

Each hinge plate carries a pawl finger 53, 54, and it will be appreciated that these travel vertically with the carrier block and normally lie in the positions shown in full lines in Figure 3, but that each such pawl finger is movable inwardly to the position shown in dotted lines in that view with inward swinging of its supporting plate.

The carrier assembly just described travels in a vertically disposed column-like path behind the panel and on either side of this path are a plurality of valve elements, spaced vertically from one another. One of such valve elements is shown in section in Figure 3, its body being generally designated 60. Each of these valve elements is provided with an actuating pawl 62 engageable by one of the pawl fingers as 53. One such valve, termed a "panel control valve," is provided for each blower unit or other controlled device whose action is to be regulated by the system.

The details of construction of the panel control valves will subsequently be considered in greater detail, but in connection with the mode of actuation thereof, it is to be noted that the internal valving means is operable by a plunger 64 which projects yieldably from the end of the casing 60 of the valve toward the path of the carrier-supported finger 53 or 54, as the case may be. Pawl 62 has a heel portion 65 engageable with plunger 64 as shown in Fig. 6.

Each pawl 62 is loosely carried by a horizontal shaft 66 which is perpendicular to and extends forwardly through the panel 20, where it carries a rigidly attached knob as 68 overlying and adapted to be manipulated from the front of the panel. Fast upon the shaft beside the pawl 62 is a sector piece 70 having a pin 72 projecting from one face thereof into a slot-like opening 74 in the pawl. As best shown in Figure 6, the opening 74 is of relatively large size so that the pawl is of generally inverted U-form.

When the shaft 66 and sector 70 are in the normal operating position in which the parts are shown in Figure 6, the pin 72 holds the pawl 62 in the raised position shown in Figure 6 in which the inner end of the pawl extends angularly downwardly and inwardly and into the path of movement of the pawl finger 53. The sector and pin are releasably held in such position by a spring detent finger 75, which at such time frictionally engages in a relatively shallow detent notch 76 in the periphery of the sector 70. When

the sector is turned clockwise (as the parts are viewed in Figure 6), the pin 72 is moved angularly downwardly and the pawl falls under gravity to the dotted line position shown in that view. The pawl is so contoured that at such time it does not project inwardly far enough to lie in the path of vertical movement of the pawl finger, and the pawl finger may then travel freely past the flat face 78 of the pawl, which at such time is approximately vertical. With the pawl in the normal operating position shown in full lines in Fig-

ure 6, the pawl may be rocked slightly counter-clockwise upon its shaft when its lower extremity 89 is engaged by the pawl finger. Such upward rocking movement of the pawl is induced by the piston weight 30 and causes the heel 65 of the pawl to push the plunger 64 inwardly.

Positioned adjacent and shown as secured to each of the valve bodies corresponding to the valve body 60 is a pawl finger releasing mechanism comprising a housing 88 which carries a plunger 85 projectable to engage the hinge plate as 45. The plunger is operable by a bellows 86 to the head of which the plunger is attached. The bellows is sealed at one end to the housing 88. Actuating air pressure is adapted to be delivered to housing 88 by means presently to be described. Each such release mechanism is positioned to contact with its adjacent valve assembly as 60 in such manner that the plunger 85 is engageable, when projected, with the outer face of the hinge plate as 34, when the carrier is in the position in which its pawl finger as 53 is in engagement with the pawl as 62 for the corresponding valve unit. A spring 90 within the bellows normally retracts the plunger 85. The release cylinders are secured as by screw means 61 to individual bracket plates as 63 through which the release plungers 85 project. The panel control valves are secured to the same bracket plates, as by screw means 67. The bracket plates are carried by vertical rails 69, 71 mounted on the rear face of the panel on opposite sides of and spaced from slot 24.

It will be understood that panel control valve parts and pawl finger release parts are duplicated for each blower or group of blowers to be controlled from the panel, although parts on opposite sides of the slot 24 are symmetrically opposite in their arrangement. Detailed redescription of the duplicated parts will not be required.

As best shown in Figure 2, the knobs 63 may have pointer-like projections 69, and these are so positioned and the parts are so proportioned that when such pointers are horizontal, the pawl carried by the same shaft as the knob is held in the ready position or lifted position equivalent to that shown in Figure 6, while when the knob is turned 90° in a direction to move the pin 72 downwardly away from the pawl and to cause the pointer to assume a vertical position, the pawl drops to the inoperative dotted line position of Figure 6, in which its valve is not actuatable by the carrier.

The control panel frame assembly also carries a start and stop valve 95, shown as located near the top of the slot 24 and provided with an upwardly projecting plunger 96 by which it is operable. The details of this valve will also be considered presently, but referring to the manner of mechanical actuation thereof, it will be observed that an actuating arm 98, pivoted upon a pin 100 carried by a rigidly supported bracket 102 attached to the side of the valve casing 95, overlies the plunger 96 and is movable downwardly to open the valve by depressing the plunger 96. When moved upwardly, the arm frees the plunger and allows the same to rise and the valve to close. A spring 103 urges the arm 98 downwardly with sufficient force to depress plunger 96 and open the valve.

The arm 98 is adapted to be latched in the raised position in which the valve is closed by means of a latching dog in the form of a triangular sheet metal plate 110 pivoted upon a pin 112 carried by a guide block assembly 106, fixedly secured to the frame structure behind the panel 20 as by the screws 113. The plate 110 is

provided with a latching shoulder 114 movable to and from a position in which it underlies the arm 98 to hold the arm in the raised, valve-closed position, while when the plate is rocked free of the arm, the spring 103 pulls the arm down and opens the valve. That portion of the arm engageable with the latch is also guided in a slot 107 in the guide block assembly 106. A tension spring 115 urges the latch plate to latched position. A rod 105 is pivotally connected to the plate 110 and extends downwardly beside the slot 24. At its lower end the rod 105 has a laterally bent foot portion 104 which is engageable by the block 26 when the block is pushed down to the lower limit of its travel. The rod 105 is positioned and guided by suitable slide bearing bracket means as 116. The arm 98 has a finger portion 108 at its outer end which also projects into the path of the carrier blocker 26 at the upper limit of travel of the block, so that as the block reaches such upper limit, it engages and lifts the arm 98 to the valve-closed position. It will be appreciated that when the arm is thus raised above the shoulder 114, the latch plate 110 is rocked clockwise as viewed in Figure 10, to latch the arm in the raised position. When the block is pushed all the way down, it engages the foot 104 and, by pulling down on the rod 105, rocks the latch plate in the opposite direction or counterclockwise to move the shoulder 114 from beneath the arm 98, allowing the arm 98 to be pulled down by spring 103 to open the valve.

A source of air under pressure is connected to the valve 95. The source may comprise a tank 354 within which the pressure is maintained by suitable compressor means (not shown) and to which connection is made by means presently to be considered in greater detail but which includes a conduit 310 leading to the lower end of the valve. The supply pressure delivered by the regulating valve 305 is indicated by a pressure gage 125 supported upon the panel 20 and connected to the supply system at a point below the interrupter valve 308 by means of a conduit 126.

The air enters the lower end of the body of valve 95 by way of an axially disposed chamber 128 containing a ball valve 130 which is urged toward closed position by a compression spring 132 beneath the valve as well as by the air pressure. The valve body also contains an axial passage 134 connecting chamber 128 to a similarly positioned chamber 140 at the opposite end of the body. Within passage 134 is a pin 135 movable downwardly to open the valve 130 when the plunger 96 is depressed. Plunger 96 is engageable with a second ball valve 136 in the upper chamber 140, the pin 135 between the two valve balls being of such length that only one ball can be seated at a time. The pin 135 is enough smaller than passage 134 so that air may move freely through the passage when either ball is unseated. An exhaust passage 138 connects the outside of the casing 95 with the chamber 140, while the central passage 134 is connected by means including a lateral passage 142, coupling 144 and conduits 120, 145 to a pressure reducing valve 146. The pressure reducing valve 146 is also supported by the panel 20 and may be of any suitable or commercially available variety.

In the preferred embodiment disclosed, the pressure supplied to the start-stop valve 95 is maintained at approximately 80 pounds per square inch by a pressure regulating valve 305 and a pressure controlled interrupter valve 308, while the pressure reducing valve 146 maintains

the pressure in the output conduit 150 from that valve at a pressure of approximately 35 pounds per square inch. The reduced pressure air from the reducing valve 146 may also be connected as by means of a coupling 152 to a pressure gage 154 mounted upon and visible from the front of the panel.

The reduced pressure air from the regulating valve 146 may be led directly to manifolds as 155, 158 connected to the inlets of some or all of the panel control valves, but such direct connection is only employed where it is desired to start the operation of the first of the blowers connected to such manifold immediately upon the opening of the start-stop valve. Such immediate starting is feasible in the case of blowers employing air as the blowing medium, and in the illustrative arrangement depicted in Figure 1, all of those blowers which are controlled by the valves connected to the manifold 158, at one side of the panel, employ air for blowing. At the other side of the panel, the manifold may be formed in two sections, comprising an upper section 155, the blowers connected to which also employ air for blowing, and a lower section 155A, the blowers connected to which employ steam for blowing. Manifold section 155 is directly connected to the conduit 150 from the reduced pressure air supply source, represented by the reducing valve 146. To prevent delivery of steam to the steam blowers connected to manifold section 155A until the removal of condensate from the steam supply system, a timed delaying device is interposed between manifold section 155A and the valve 146 to prevent delivery of air to manifold section 155A for a time adequate for the draining of condensate from the steam lines. The time delaying means will presently be considered in greater detail, but it includes a valve 315 connected to an output conduit 325 from regulating valve 146 and in turn connected to manifold section 155A by a conduit 327.

As previously indicated, the panel control valve assemblies are supported in vertically spaced relation by and upon the back of the panel 20 in such manner as to be successively actuatable by the pawl finger 53 or the pawl finger 54 of the carrier 26. One such valve is shown cross-sectionally in Figure 3 and the body thereof is generally designated 88. It will be understood that all such valves and their appurtenances may be of like construction and that description of one will suffice.

The construction of the valve 60 will be seen to be generally similar to that of the start and stop valve 95, previously described. The low pressure air enters the axially disposed chamber 162 at the rear or manifold end of the valve through the coupling 164. Chamber 162 contains a ball valve 166 and a spring 165 which urges the valve ball against the seat formed by the outer end of the reduced central passage 168. When the ball 166 is off its seat, communication is established between the low pressure source and a conduit 170 connected by the coupling 172 to a lateral passage 174 communicating with central passage 168. Passage 168 communicates at its opposite end with a chamber 175 which is also larger than the central passage so that a seat is formed at the juncture of passage 168 and chamber 175 for a ball valve 176 arranged in the latter chamber. A stem 178 which is longer than passage 168, but of substantially lesser diameter than such passage, prevents the seating of more than one of the ball valves 166, 176 at a time, unseat-

ing the opposite ball whenever either of the balls moves into engagement with its seat. An exhaust port 180 in the valve body 60 connects chamber 175 to atmosphere. Chamber 175 extends as a straight bore of uniform diameter to the inner end of the valve body and slidably supports the actuating plunger 64 previously referred to. Plunger 64 is engageable with the valve ball 176 and when pushed inwardly forces the ball 176 against its seat and the ball 166 off its seat. The plunger is engageable by the pawl 62 as previously described. It will be seen that when the pawl is lifted by the pawl finger 52, the plunger 64 is forced inwardly to close valve 176 and open valve 166, establishing communication between the low pressure source and the conduit 170, while when the pawl is released by the pawl finger, valve 166 closes under the influence of air pressure supplemented by the spring 165, valve 176 being opened to vent the conduit 170 to atmosphere by way of passages 174, 168 and 180.

In the case of each of the valves corresponding to the valve just described, a continuation of the conduit corresponding to the conduit 170 connected to the valve outlet extends to the remotely located controlled apparatus or blower unit which is controlled by the valve in question and is termed the "control line" or "control conduit." Each of the conduits 170 is connected to a fitting and coupling member 185 carried by the bellows casing 88, and the control conduit as 186 is connected to coupling member 185. As previously explained, the reduced pressure air delivered to the bellows casing 88 from the low pressure source is incapable of collapsing the diaphragm 86 to release the pawl finger 53 from engagement with the pawl 62, but upon a sufficient increase of pressure in the control line, the bellows is collapsed, overcoming the resistance of the distending spring 93 to project the release pin 85 into engagement with the hinged arm 45 which carries the pawl finger.

Each control conduit as 186 extends to the diaphragm housing 188 of a diaphragm-operated valve as 190 (Figs. 1 and 3) which controls the delivery of power air to the blower actuating motor. In the case of control line 186, it is assumed that the blower to be controlled is one which rotates in one direction only and is not reciprocable. It is also assumed that the air motor 192 which drives the blower also drives at half speed a timing gear 248 connected to the motor through the agency of a suitable mechanical connection not necessary to be considered in detail but which includes a motor-driven pinion 241 meshing with the timing gear. The operating mechanism of the valve 190 is such that the valve is adapted to be opened by the application of the reduced pressure (e. g. 35 pounds per square inch) control air to the diaphragm chamber 188. Valve 190 controls communication between the source of air under pressure of approximately 80 pounds per square inch, and an air motor 192 which drives the controlled soot blower. The power air for the motor is delivered to the valve 190 through a conduit 194, and a conduit 195 extends from the valve 190 to a motor control valve shown in Figure 13. The casing of the motor control valve is generally designated 196.

The motor control valve casing 196 may be mounted directly upon or adjacent the air motor 192, and the motor in turn is so connected to the valve as to actuate the same to a position to interrupt the supply of power air to the motor after the motor has turned through a desired angular

interval. The power air line 195 is connected to a side port 198 formed in the valve casing 196 and which communicates with a cylindrical chamber 200 in the valve casing. The chamber contains a slideable poppet valve 202 normally held in a raised position by a compression spring 204 beneath the valve so that the power air passes under the valve and out a port 206 on the other side of the valve, whence it is conducted by way of a conduit 208 to the motor 192. Valve 202 is carried by a stem 210 which projects from the valve casing to serve as a device for manipulating the valve. When the valve is in the raised position, it interrupts communication between the power air line 195 and a valve port 212 which extends through the side of the valve casing above the valve chamber 200, while when the valve is pulled down, communication is established between the ports 198, 212 through an upward and coaxial continuation 214 of the chamber 200. The chamber 200 is substantially larger than the valve, as shown, to allow free air flow around the valve, while the upper continuation section 214 of the chamber is smaller than the valve, as also is the lower continuation portion 215 which houses the spring 204 and which provides communication between the valve chamber 200 and the port 206. Shoulders 216, 218 are thereby provided between the main valve chamber portion 200 and the extension portions 214, 215, respectively, the valve 202 when raised seating against the shoulder 216, and when lowered seating against the shoulder 218.

The port 212 is connected by a conduit 220 to an orifice member 222, which is in turn connected to the control conduit portion 186.

As previously indicated, the power air for driving the motor is at a higher pressure than the control air delivered to the diaphragm chamber 188 by way of the control conduit 186. When the valve 202 is pulled down, therefore, the higher pressure air from the air power line 195 is delivered to the conduit 220 by way of valve passages 214, 212, and the pressure is thereby raised in the control line 186.

When the pressure in the control line reaches a predetermined value, which may be of the order of 55 pounds per square inch, due to downward movement of valve 202, the corresponding pressure within the bellows casing 88 connected to the line 186 (which is the upper left-hand unit as the parts are viewed in Figure 4), overcomes the spring 90 and collapses the bellows diaphragm 86 sufficiently to cause the plunger 85 to push the pawl finger supporting arm 45 inwardly, moving the pawl finger 53 from beneath the pawl 62, thereby allowing the pawl to drop and the ball valves 166, 176 to move to the right, closing the valve 166, and interrupting communication between the low pressure air source and the control line and venting the control line to atmosphere through valve chamber 175 and exhaust passage 180. By reason of the inclusion of the orifice member 222, the pressure in the control line 186 is vented through the exhaust passage 180 more rapidly than the pressure can be maintained through the orifice in the member 222, and when the control line pressure and the corresponding pressure in the diaphragm chamber 188 fall away sufficiently, the diaphragm-operated valve 190 closes, interrupting the high pressure air supply. As the pressure continues to fall away in the control line and in the connected conduit 220 and the upper valve chamber 214, valve 202 is again lifted to re-engage the upper seat 216, reconnect-

ing the air motor to the high pressure supply line 195, so that the unit is ready to restart when the pawl 62 is again actuated.

It will be understood that when the pawl finger 53 is freed from the pawl, the carrier 26 and parts carried thereby are released and rise under the influence of the counterweight 30. If there were any other panel control valves positioned above the one connected to line 186, one of the pawl fingers 53 or 54 would engage the pawl of the next higher valve having its pawl in the operative position, and such next pawl in the sequence would then be raised to initiate operation of the blower head controlled thereby in like fashion.

15 In the shown arrangement, however, line 186 is connected to the highest panel control valve, so that when the carrier is released by its tripping pin 85 the carrier rises to engage and lift the finger 198, allowing the valve 95 to close to shut down the system.

The blower control means shown in Figure 13 also incorporates mechanism for actuating the valve 202 when the blower head is in predetermined angular positions. A timing gear 240 is 25 driven in timed relationship to the blower nozzle and may be geared or otherwise positively related to the blower nozzle by any suitable means not necessary to be disclosed in detail herein, since such mechanical features do not form a part of my present invention. The timing gear 240 carries a trip pin or lug 242 engageable once during each revolution with a valve actuating arm 244 when such arm is in an operative position, although as will be seen such arm is movable into and out of the operative position. Arm 30 244 is pivoted as at 245 to a support 246 which carries the valve, timing gear, and associated mechanism. The arm 244 is also rockable in a plane perpendicular to the plane of the gear 240 and perpendicular to the stem 210 through a limited arc sufficient to move the arm into and out of that part of the path of the lug 242 farther from pivot 245. The stem 210 extends through an arcuate transverse slot 250 in the arm 244, 35 which slot is long enough to permit such lateral movement of the arm. The arm is movable transversely of the gear into and out of the path of lug 242 by a piston 252 movable in the cylinder 254 in a path parallel to the axis of the gear 240. 40 In Figure 13, the cylinder and piston 254, 252 are turned 90° about an axis parallel to the arm 244 so that they may be shown in the plane of the paper, although they are actually perpendicular to such plane, as shown in Figure 14, so that 45 when the cylinder is energized the arm may be moved inwardly into the path of the lug, and vice versa. The arm 244 is centrally offset as indicated at 243 so that only the part thereof shown at the right in Figure 13 is engageable by the lug. 50 The arm 244 projects into a lateral slot 255 in the piston 252 and through a clearance opening 256 in the cylinder. The slot 255 forces the arm 244 to move with the piston in an axial direction to carry the arm into and out of the path 55 of travel of the lug 242, but permits the arm to swing about the axis of pin 245 to the extent necessary to actuate the valve 202. The arm actuates the valve in a downward direction only, as the parts are shown in the drawing, acting upon the stem 210 through an adjustable abutment carried by the lower end of the stem and comprising a pair of jam nuts 258 and a compression spring 260 on the stem between the arm and the jamb nuts.

60 70 75 The piston 252 and arm 244 are urged out-

wardly away from the gear 240 by a spring 261 within the cylinder 254 and bearing outwardly against the bottom of the piston. Spring 261 yieldably maintains the arm 244 out of the path of movement of lug 242 except when fluid under pressure is delivered to the space within cylinder 254 above the piston 252 through a conduit 264, which connects the head of the cylinder to the port 265 formed in the valve casing 196 and communicating with the valve chamber 200. By virtue of this arrangement, the arm 244 is maintained in the path of the lug 242 at all times while the valve 190 is open. If the timing gear 249 is driven at half the speed of the blower nozzle, it will be appreciated that since the lug 242 commences to rotate clockwise, as the parts are shown in the drawing, from an initial position under and close to the arm 244, each time the blower unit is started in response to initial delivery of motor power air to the valve 196 and air motor 192 through conduit 195, the blower nozzle will make two full revolutions to carry the pin 242 through approximately one full revolution before the lug 242 re-engages the arm 244. When the air motor is in operation, the arm 244 is held in the path of movement of the lug 242 by the piston 252 in the manner described. As the motor completes the driving of the nozzle through its intended arc of rotation, the lug strikes the top of the arm, as the parts are shown, thereby moving the valve 202 down from the position shown in full lines to the position in which it seats against the shoulder 218 to deliver the higher pressure air to the control line and trip the releasing means at the panel board to shut off the diaphragm-controlled valve 190 in the manner previously described.

In so actuating the valve 202, the arm 244 compresses the spring 260 somewhat, since the motor cannot be instantly stopped and spring 260 permits some overtravel. When the pressure is relieved in the cylinder 254, therefore, and spring 261 lifts the arm 244 clear of the lug 242, the pressure previously exerted upon the spring 260 by the arm 244 is relieved, and arm 244 springs back in response to the expansion of the spring 260 far enough to overlie the lug 242. When the unit is again started, therefore, the arm 244 is not in a position to block the lug 242 and the lug moves out from under the arm 244 and continues for a full revolution, as previously stated, before re-engaging the arm 244. Before the lug has completed its orbit, however, the piston 252 has again pushed the arm downwardly into the path of the lug. It will be understood that if it is desired to permit the blower to turn through a shorter arc, additional lugs may be secured to the timing gear as indicated in dotted lines at 242a.

Figure 1 shows the applicability of the principles of this invention to the control of a plurality of blowers of different types, some of the blowers employing steam as the cleaning medium and some utilizing air as the cleaning medium, while the air blowers may operate at different pressures. All of the blowers are air controlled and air driven.

The motor driving and control air is supplied to the system from a suitable source which may comprise a tank 354 within which pressure is maintained by one or more compressors and suitable control apparatus which may of course vary widely without departing from the present invention, but a suitable arrangement of which will presently be indicated. The air delivery pipe from such source is designated 399 and the air

passes first through a hand valve 302, a filter 304 and a pressure regulating valve 305, which may be set to maintain an output pressure in the neighborhood of 80 pounds per square inch.

5 From the pressure regulated output of the valve 305, the air is taken through a conduit 306 to a pressure controlled valve 308 and thence to the conduit 310 which leads to the start-stop valve 95 mounted upon the panel 20, as previously described.

10 The pressure controlled valve 308 is operable by a diaphragm unit 312 connected by means including a conduit as 314 to the tank 356 or other source of pressure air supply. Valve 308 is ar-

15 ranged to interrupt communication between conduits 306, 310 whenever the pressure in the supply tank drops below a predetermined value and to re-open when the desired value is again reached. This prevents the starting of any blow-

20 ing unit whenever the pressure at the source is too low, and allows my improved blower control system to be used with receiver tanks of limited capacity, interposing delay whenever necessary in the operation of the blower system to allow the pressure to build up in the air supply system.

25 The reduced pressure control air from regulating valve 146 is conducted to the right-hand manifold 158 and to the upper left-hand manifold section 155 through conduits 150, 156, as noted previously, but the lower left-hand manifold section 155A is connected to the pressure regulating valve 146 through time delay means including a pressure controlled valve 315, the action of which is regulated by a timing mechanism consisting of

30 a calibrated receiver 316 connected to the dia-phragm-type operating unit 318 for the valve 315 by a conduit 320, conduit 320 being connected to the output of the start-stop valve 95 through a supplemental start-stop valve 504 by way of a re-35 striction orifice member 322 and conduits 502, 324, the latter connected to the output conduit 145 from the main start-stop valve 95. The function of the supplemental start-stop valve 504 will presently be considered, but assuming that both of the valves 95, 504 are open, the rate of pressure

40 build-up in the system comprising the tank 316 and actuating diaphragm chamber 318 is determined by the orifice in the member 322, while the time required to build up to the actuating pressure is determined by the capacity of the tank 316. When the actuating pressure is 45 reached, the normally open valve 315 closes to establish communication between the reduced pressure control air supply source and the manifold section 155A.

50 The time delay mechanism just described is employed because the blowers whose action is governed by panel control valve means connected to manifold section 155A utilize steam for blowing, and the delay thus interposed insures a sufficient

60 interval for the escape of condensate through the impulse trap 420. A steam blower 334 is shown connected to the lowermost panel control valve, designated 338, connected to manifold section 155A. Steam is supplied to blower 334 through a diaphragm-operated valve 328. The actuating diaphragm chamber 326 of the valve 328 is also connected indirectly to the output from the start-stop valve 95 through the supplemental start-stop valve 504. The valve 328 receives blow-

65 ing steam from a suitable source, not shown, through pipe 330 and, when open, delivers the steam through a pipe 332 to the blower unit generally designated 334. The details of construction of the blower need not be considered since they form no part of my present invention,

although a suitable blower is disclosed in the copending application of Le Roy S. De Mart, Serial No. 766,183, filed August 5, 1947. The continuation 335 of the pipe 332 may lead to the blowing steam inlets of other steam blowing units, the action of which may be controlled by other control valves connected to the lower manifold section 155A.

The action of the blower 334 is controlled through the control line 336 which may correspond to the control line 186 previously described in its general connection and arrangement and which is connected in like fashion to the output of a control valve 338 comprising one of the three-way control valves carried by the control panel corresponding to the valve 60 previously described.

When the valve 333 is opened in the course of operation of the valve-actuating carrier assembly 26 of the control panel, control pressure air is not introduced to the line 336 until the time delay mechanism has completed its operation and opened valve 315, but when valve 315 opens, air passes through line 327, manifold section 155A, valve 338 and conduit 336 to the diaphragm-operated valve 340 corresponding to the valve 199 previously described. Valve 340 is thereby opened by the introduction of such pressure to the actuating diaphragm chamber 342, and the blower actuating motor 344 is operated to open the steam valve in the blower head and to rotate and/or reciprocate the blower unit as the case may be and in accordance with the details of construction of such blower. The control valve for the blower motor is designated 345 and it will be appreciated that if the blower unit is of the type which is rotatable but not reciprocable, valve 345 may correspond in construction to the valve 196 previously described, while if the blower unit is of the reciprocating-reversing type, the valve may correspond to the disclosure of the copending application of Le Roy S. De Mart, Serial No. 60,435, filed November 17, 1948. In either event, the control connections are the same, but with the motor 344 of the reversing-type, two connections are required from the motor control valve 345 to the motor 344, as shown, since one motor port cannot be directly discharged to atmosphere as in the case of the irreversible motor 192. The orifice member 346 in the return conduit 348 from the motor control valve 345 corresponds to the orifice member 222 previously described.

Blowers employing air as the blowing medium are diagrammatically indicated in Figure 1 at 350 and 360. Blowing air is supplied to the blower 350 through a conduit 352 connected to a high pressure tank 354. The tank 354 is adapted during operation of the system to be maintained at one pressure for a predetermined interval during which certain of the air-operated blowers are functioning, and at a different pressure while other blowers are operating. For example, the blower 350 may be designed to operate with air supplied at 350 pounds per square inch, and while this and similar blowers are operating, the pressure in the tank 354 is maintained at 350 pounds per square inch, while other blowers as 360 also utilizing air as the blowing medium may be arranged to operate at a lower pressure, for example, 250 pounds per square inch. The automatic regulating means which controls the pressure in the tank 354 is so arranged as to maintain the pressure in tank 354 at 250 pounds per square inch during the operation of blowers such as the blower 360. The pressure air supply for

the tank 354 is obtained from a higher pressure tank 356 through a variable output pressure-controlled reducing valve 358. The action of the valve 358 is regulated by a dual-pressure control assembly, generally designated 365, the construction of which forms no part of my present invention, and in fact it will be recognized by those skilled in the art that suitable dual-pressure control devices are commercially available. Generally considered, however, the control unit comprises a pair of pressure control devices 368, 370 supplied with air at constant pressure through a pressure regulating valve 372 connected by a conduit 374 to the tank 354. Conventional filtering

and gage means designated 375, 376, respectively, may be incorporated in the inlet line 374 to the pressure control unit. The control device 368 may be adjusted to deliver an output pressure of 250 pounds per square inch, and the control device 370 may, for example, deliver an output pressure of 350 pounds per square inch. A diaphragm-operated three-way diverting valve 378 has one inlet connected to a conduit 380 from the pressure regulator 368 and another inlet connected to a conduit 382 from the pressure regulator 370. The outlet of the valve 378 is connected by a conduit 384 to the actuating diaphragm chamber portion 385 of the valve 358, while the valve 378 has an actuating diaphragm portion 386 by which the valve is operable to alternatively connect the conduit 384 to either the conduit 380 or the conduit 382, the arrangement being such that when actuating pressure is delivered to the diaphragm chamber 386 through the conduit 388, the valve 378 provides connection between conduits 382, 384 only, while when the pressure is relieved in the chamber 386, the valve 378 connects the line 384 only to the line 380.

Air under pressure is supplied to the main storage tank 356 from suitable compressor means, not shown, through a conduit 390, and the tank 356 is connected by a conduit 392 through a hand valve 394 and regulating valve 358 to the dual pressure supply tank 354.

It will be understood that one or more additional valves shown at the left side of the panel diagrammatically illustrated in Figure 1 may also be arranged to control steam blowers, and these are also connected to manifold section 155A, as for example valve 424, but the control valves 402, 404, 405 and 60 shown at the right in Figure 1 are all for air blowing units, as also are the valves connected to manifold section 155. These panel valves are also connected to their respective blowers by individual control lines as 395, 396, 398 and 400. Each of these panel valves is connected to its manifold through a check valve at 408 which prevents back flow through the panel valve to the manifold.

Valves 404 and 60 are arranged to control the action of blowers utilizing blowing air at 350 pounds per square inch, while valves 402, 405 are to control the action of blowers utilizing air at 250 pounds per square inch. The control lines 395, 398 are connected directly to the diaphragm chambers for their respective motor air control valves as 410. This will be seen to correspond to the arrangement of the control line 186 previously described connected to diaphragm chamber 188. It will be recognized that valve 410 and the motor control valve 412 may correspond either to the parts shown in Figure 13 or to the parts 340, 345 employed to control the steam blower 334, an equivalent orificed control member 414

also being connected between the motor control valve 412 and the control line 398.

Each of the control lines 396, 400 from the control valves 404, 60 for the higher pressure air blowers is connected through a check valve as 415, 416 to the conduit 388 leading to the actuating diaphragm chamber 386 of the valve 378. All of the air blowers are supplied with blowing air from the tank 354 through a common pipe 352 suitably branched, as shown, for connection thereto, but when the lower pressure blowers as 360 are in operation, since there is no control air connection to the diaphragm chamber 386, the valve 378 connects the 250 pound controller 368 to the diaphragm chamber 385 of regulating valve 358 so that the air is delivered to the tank 354 at a rate such as to maintain the pressure therein at 250 pounds per square inch. When one of the 350 pound blowers as 350 is in operation, the control air in its controlling line as 400 is also delivered to the actuating diaphragm chamber 386 of the valve 378 and the latter valve then connects the 350 pound controller 370 to the regulating valve 358, which opens sufficiently to deliver added pressure to the tank 354 and raises the pressure therein, and in the lines leading to the blowers, to 350 pounds per square inch for operation of the high pressure blowers. The check valves 415 and 416 prevent back flow from one control line to another and so prevent unwanted air supply to a controlling line of a unit which is not supposed to be in operation.

The check valves 408 prevent such an unwanted reverse connection from one control valve to another in event the pressure controlled valve 308 closes to allow the pressure to build-up in the system as previously explained.

When the system is to be started, the carrier is pushed down to the bottom of the slot 24 to open the start-stop valve 95 as previously explained, and also to open supplemental start-stop valve 504. The carrier is then released so that it can rise under the influence of the weighted piston 30. Assuming that the pawls for all of the control valves are set in their operative positions, the carrier first opens the control valve 402 which is shown as arranged to control the operation of a low pressure air blower, which starts without delay. As soon as the valves 95, 504 are opened, pressure commences to build up in the timing receiver 316 and the steam valve 328 is opened to supply steam to the lines 332, 335 leading to the steam-operated blowers, although the valves in the blower units themselves remain closed. During the time required for the timing receiver to build-up pressure sufficient to open the pressure controlled valve 315, condensate forming in the steam lines 332, 335 may be drained by suitable means such as a conventional impulse trap device indicated at 420. After blowing of the unit (not shown) connected to the control line 395 is completed, the carrier rises to engage the pawl of valve 338 to open that valve so that air can flow into the control line 336 leading to the steam blower unit 334. If the timing interval determined by the receiver 316 is not completed, the opening of valve 338 has no effect since valve 315 remains closed and no air can enter the control line 336. The carrier accordingly remains in the indicated position, while the timing function is completed and also while the blower 354 starts and runs through its operating cycle. Thereafter the carrier again resumes its upward movement, next actuating the valve 404 which controls one of the high pressure air blower units in

the manner previously described. It will be recognized that the blower whose operation follows the air blower connected to the valve 404 is the blower (not shown) connected to valve 424 and that the control line 425 connected to valve 424 is supplied with control air without delay, since the timing system controlled by the receiver 316 only functions when the system is first put in operation.

- 10 It will be appreciated by those skilled in the art that where retracting-type blowers are used, it would be undesirable to allow a blower of this type to remain in the projected position in event valve 308 should close before completion of the full cycle of operation of such a blower. To overcome the danger of damage to a retractable blower which such a situation would entail, I provide means adapted to form a holding connection, maintaining the air supply to the control panel 20 in event valve 308 closes, until any blower which happens to be in operation at the time of such closing has completed its full cycle of operation. It will be understood that this insures the retraction of all blowers to safe positions. The 25 holding connection includes a holding valve, the body of which is generally designated 450, connected to a continuation 301 of the air supply line 300, beyond the point at which the branch conduit 306 to the valve 308 is connected, but in a 30 position such that all of the power motor air must flow through the holding valve. A conduit 452 connected to the holding valve leads to the conduit 310 so that valve 450 and conduit 452 may form a shunted connection around the 35 valve 308.

The details of construction of the holding valve are shown in Figure 15. As there indicated, the power motor air enters the right side of the valve through the conduit 301 and acts upwardly upon 40 a weighted piston 454. When air in substantial volume is flowing through the system to one of the air motor supply conduits as 455 or 456, the piston 454 is lifted, raising a valve-like boss portion 458 formed upon the bottom of the piston 454 free of its guiding opening 465 in the casing, and the air flows out to the air motor supply conduit 456 through a port 460 formed in the opposite side of the valve. Also carried by and projecting downwardly from the weighted piston 454 50 is a needle valve 462 which is held off its seat by the lifting of the piston when air is flowing through the motor supply line, as indicated, but which drops into engagement with its seat portion 464 at the bottom of the valve housing when 55 the substantial flow required by a blower driving motor is interrupted. The port 464 controlled by the needle valve is connected to the conduit 452. It will be appreciated that, this valve being gravity operated, it should be installed in the 60 vertical position, and it will also be understood that the port 464 is of sufficient size to provide a sufficient supply of air to the control panel when the needle valve is open. It will be observed that the boss portion 458 is of cylindrical 65 form and of lesser diameter than the piston portion 454. Portion 458 has an easy sliding fit in the coacting cylindrical portion 465 formed in the valve casing, but these parts do not form a tight seal, so that a relatively gradual pressure 70 equalization can take place to permit the piston to fall after all of the diaphragm valves in the motor air lines have closed. The cross-sectional area of the portion 458 is sufficient so that when 75 a diaphragm valve as 190, 410 or 340 in a motor air line opens, the differential pressure beneath

port 458 is sufficient to lift the piston, while when the piston is raised a lesser pressure will hold it up due to the larger piston area directly subject to the pressure of the air supply.

Where the system includes a considerable number of blowers, most of which employ air for blowing and only a few utilize steam, it is desirable to provide supplemental automatic valving means to control the flow of blowing steam in such manner that the steam is delivered to the blower steam piping only when needed, and is cut off after completion of the operation of the steam units, even though the air units continue operation.

In the arrangement shown diagrammatically in Figure 1, it is assumed that only the blowers connected to the control valves 338 and 424 utilize steam for blowing, and that the other blowers discharge air. The diaphragm chamber 326 of the valve 328 is not connected directly to the start-stop valve 95, but is connected by a conduit 502 to the outlet of the supplemental steam unit start-stop valve 504, which is in turn connected by the conduit 324 to the main start-stop valve 95. The construction of the valve 504 may correspond to that of the valve 95, but as best shown in Figures 4, 5 and 16, it is mounted near the lower extremity of the travel of the carrier 26 and so arranged that valve 504 may be opened by the carrier as the carrier reaches the bottom of the slot 24. The valve 504 may be carried by the bracket 34 which supports the dashpot cylinder 32. When the plunger 506 is raised, the valve 504 interrupts communication between conduits 502, 324 and vents the conduit 502, allowing the diaphragm valve 328 and the timing valve 315 to close. When the plunger 506 is depressed, it closes the vent (not shown) of valve 504 and connects the diaphragm chamber 326 to the air supply to open the steam valve 328, as previously described. The plunger 506, as in the case of the plunger 96 of the valve 95, is normally raised by an internal valve spring, but the valve is adapted to be opened by an arm 508 pivoted upon the bracket 510 fastened to the side of the body of valve 504 and overlying the plunger 506. At the lower limit of the travel of the carrier, a block 512 attached to the carrier is engageable with the end of the arm 508 to move the same downwardly and open the valve 504, and when the arm 508 is moved all the way down to the valve-open position, a latch piece 514 pivoted at 515 upon a fixed supporting bracket 516 attached to the bracket 34, swings to an overlying position with respect to arm 508 to hold the same down and keep the valve 504 open. The latch piece 514 is in the form of a bellcrank having a generally horizontal actuating arm 518 projecting forwardly toward the panel 20. A wire link 520 is secured to the arm 518 directly behind the panel and extends upwardly to a latch release arm 522 pivotally supported by the panel frame assembly and engageable by a trip dog 524 carried by the carrier during upward travel of the latter. In the illustrative arrangement depicted wherein only the valves 338 and 424 are connected to steam units, the release arm 522 may be positioned just above control valve 424 so that after the carrier is released by the release bellows plunger of valve 424 and rises therefrom to allow valve 424 to close, the dog 524 on the carrier strikes the release arm 522 to urge the same upwardly together with the link 520 and arm 518, thereby releasing the latch piece 514 from engagement with plunger

actuating arm 508 and allowing the valve 504 to close. A compression spring 517 trapped upon plunger 506 beneath arm 508 urges the arm 508 upwardly and so augments the effect of the valve spring (not shown). As the carrier continues upwardly to sequentially control the operation of the remaining air blower units after leaving the valve 424, the steam is cut off in the steam blower lines by the resultant closing of steam valve 328. This avoids the wasting of steam as will be understood.

The means on the carrier for actuating the arm 522 comprises a release dog 524 of generally triangular shape extending angularly upwardly and laterally from the carrier, to which it is pivoted upon a pin 525 in such position that its upwardly and outwardly extending nose portion 526 is adapted to underengage the release arm 522 as the carrier reaches the level of arm 522, and to swing such arm upwardly to release the valve and allow the same to close as previously described. The arm 522 is swingable upwardly far enough to allow the nose portion 526 of the dog 524 to travel past it as the carrier continues its upward movement, while when the carrier is moved downwardly, the dog 524 acts like a latch piece, being cammed inwardly by the end of the arm 522 and swinging out of the way of such arm as the carrier is moved downwardly past the end of the arm.

It will be understood that if the steam units were connected to panel control valves located near the top of the panel rather than near the bottom as shown, the supplemental start-stop valve might be biased to open position rather than to closed position, but adapted to be closed and latched in the closed position by full depression of the carrier, so that the supplemental start-stop valve would remain closed until released by the trip dog, and then allowed to open to introduce steam to the steam units. In any event, it will be seen that the supplemental valve 504 insures that the steam lines are supplied only during the steam blowing portion of the cycle.

While it will be apparent that the preferred embodiment of the invention herein disclosed is well calculated to fulfill the objects above stated, it will be appreciated that the invention is susceptible to modification, variation and change without departing from the proper scope or fair meaning of the subjoined claims.

What is claimed is:

1. A sequence controller for fluid actuatable soot blowers and the like comprising a support, a traveling actuator, biasing means urging said actuator in one direction, the actuator being manually movable in the opposite direction, releasable latch-type blocking means carried partly by the support and partly by the actuator and including a plurality of blocking elements positioned in spaced relation along the path of travel of the actuator and movable into and out of positions in which they block movement of the actuator in the direction induced by said biasing means, a portion carried by said blocking element and limitedly movable by said actuator when engaged thereby, under the influence of said biasing means, a diverting device movable by and in response to such limited movement, and an independent latch releasing device appurtenant to each of said blocking elements for releasing the same from blocking engagement with respect to the actuator.

2. Means as set forth in claim 1 wherein each of said blocking elements comprises a limitedly shiftable actuating element and one of said diverting devices is provided for each blocking ele-

ment, each diverting device comprising a fluid diverting valve, individual shifting means for manually moving each of said actuating elements into and out of blocking position, each of said shifting means being provided with an observable part to permit observation of the position of said shifting means and thereby a determination of the setting of the appurtenant blocking member.

3. Means as set forth in claim 1 wherein said actuator includes a latch piece movable laterally with respect to the path of movement of the actuator but held against unwanted longitudinal movement with respect to the actuator, said latch piece being successively engageable with said blocking elements when the latter are in blocking position, and disengageable from the blocking elements to free the actuator for continued travel in response to such lateral movement of the latch piece.

4. Means as set forth in claim 2 wherein said actuator includes a latch piece movable laterally with respect to the path of movement of the actuator but held against unwanted longitudinal movement with respect to the actuator, said latch piece being successively engageable with said blocking elements when the latter are in blocking position, and disengageable from the blocking elements to free the actuator for continued travel in response to such lateral movement of the latch piece.

5. Means as set forth in claim 2 wherein said actuator includes a latch piece movable laterally with respect to the path of movement of the actuator but held against unwanted longitudinal movement with respect to the actuator, said latch piece being successively engageable with said blocking elements when the latter are in blocking position, and disengageable from the blocking elements to free the actuator for continued travel in response to such lateral movement of the latch piece, means for connecting a source of control fluid under pressure to each of said valves, means for connecting a control conduit from each valve to a controlled soot blower unit station or the like, each such valve being shiftable to connect such conduit to the source or alternatively to vent the conduit.

6. Means as set forth in claim 2 wherein said actuator includes a latch piece movable laterally with respect to the path of movement of the actuator but held against unwanted longitudinal movement with respect to the actuator, said latch piece being successively engageable with said blocking elements when the latter are in blocking position, and disengageable from the blocking elements to free the actuator for continued travel in response to such lateral movement of the latch piece, means for connecting a source of control fluid under pressure to each of said valves, means for connecting a control conduit from each valve to a controlled soot blower unit station or the like, each such valve being normally maintained in a position to vent the conduit but shiftable by the actuator to connect such conduit to the source.

7. Means as set forth in claim 2 wherein said actuator includes a latch piece movable laterally with respect to the path of movement of the actuator but held against unwanted longitudinal movement with respect to the actuator, said latch piece being successively engageable with said blocking elements when the latter are in blocking position, and disengageable from the blocking elements to free the actuator for continued travel in response to such lateral move-

ment of the latch piece, means for connecting a source of control fluid under pressure to each of said valves, means for connecting a control conduit from each valve to a controlled soot blower unit station or the like, each such valve being normally maintained in a position to vent the conduit but shiftable by the actuator to connect such conduit to the source, means for connecting a source of power fluid under a different pressure to an operative device at each controlled unit station, including a control valve at each station to which said control conduit is connected and to which said source of power fluid and the operative device are also adapted to be connected, said control valve being movable to selectively connect the power fluid source to the device to drive the same or to the control conduit to change the pressure in the latter, said latch releasing device including an operating element connected to the control conduit and movable in response to a change of pressure in said control conduit.

8. Means as set forth in claim 1 wherein each diverting device comprises a fluid diverting valve, means for connecting a source of control fluid under pressure to each of said valves, means for connecting a control conduit from each valve to a controlled soot blower unit station or the like, each such valve being shiftable to connect such conduit to the source or alternatively to vent the conduit.

9. Means as set forth in claim 1 wherein each diverting device comprises a fluid diverting valve, means for connecting a source of control fluid under pressure to each of said valves, means for connecting a control conduit from each valve to a controlled soot blower unit station or the like, each such valve being normally maintained in a position to vent the conduit but shiftable by the actuator to connect such conduit to the source.

10. Means as set forth in claim 1 wherein each diverting device comprises a fluid diverting valve, means for connecting a source of control fluid under pressure to each of said valves, means for connecting a control conduit from each valve to a controlled soot blower unit station or the like, each such valve being normally maintained in a position to vent the conduit but shiftable by the actuator to connect such conduit to the source, means for connecting a source of power fluid under a different pressure to an operative device at each controlled unit station, including a control valve at each station to which said control conduit is connected and to which said source of power fluid and the operative device are also adapted to be connected, said control valve being movable to selectively connect the power fluid source to the device to drive the same or to the control conduit to change the pressure in the latter, said latch releasing device including an operating element connected to the control conduit and movable in response to a change of pressure in said control conduit.

11. A sequence controlling and activating and deactivating system for a plurality of motor-driven soot blowers, said system including a control station and a plurality of controlled stations, the control station being connectable to a source of control fluid under pressure, each controlled station including a driving motor for a soot blower, a control conduit connecting the control station to each controlled station and adapted to convey control fluid pressure to the controlled station, a cross-connecting valve at each controlled station operatively connected to

21

the control line and to the motor and adapted to be connected to a source of motor driving fluid under higher pressure, means responsive to actuation of the motor for actuating said cross-connecting valve to increase the pressure in the control line by connecting the source of motor driving fluid to the control line, a plurality of diverting devices at the control station, one connected to each of said control lines, an actuator movably supported at the control station for successively actuating each of said diverting devices, said actuator including latch means operatively engageable with and releasable from said diverting devices, and a latch releasing element actuatable by and in response to increase of pressure in the control line.

12. In a system as defined in claim 11, a manually movable member appurtenant to each of said diverting devices for preventing actuation thereof by the actuator.

13. A system as defined in claim 11 wherein each of said latch releasing elements is fluid actuatable and connected to one of the control conduits and each of said diverting devices comprises a diverting valve normally venting the control conduit and also venting the latch releasing element but movable by said actuator to close the vent.

14. A system as defined in claim 11 wherein each of said latch releasing elements is fluid actuatable and connected to one of the control conduits and each of said diverting devices comprises a diverting valve normally venting the control conduit and also venting the latch releasing element but movable by said actuator to close the vent and connect said conduit to the source of control fluid.

15. In combination with a system as defined in claim 14, a time delaying device connected between said source of control fluid and said diverting devices.

16. In combination with a system as defined in claim 14, a pressure-responsive cut-off valve connected between said source of control fluid and said diverting devices and responsive to a fall of pressure of said source of motor driving fluid to interrupt the flow from the control fluid source.

17. A sequence controller for a plurality of soot blowers incorporated in a system which includes a controlled station for each soot blower and a common control station, a control line connecting the control station to each controlled station, a plurality of controllers at the control station, one such controller being connected to each control line, said controllers being arranged in spaced relation to one another and individually actuatable to control the connection of said control lines to a source of power, and a single common traveling actuator at the control station and movable to sequentially operatively engage each of said controllers.

18. Means as defined in claim 17 including means defining a predetermined path of travel for said actuator, said controllers being arranged upon opposite sides of said path of travel and in staggered relation to one another for successive actuation by the actuator.

19. Means as set forth in claim 17 wherein each of said controllers includes a portion operatively displaceable by the actuator, and individual disabling means appurtenant to each controller for preventing actuation of the controller by the displaceable portion.

20. Means as set forth in claim 17 wherein each

22

of said controllers includes a portion operatively displaceable by the actuator, and individual means for retracting each of said displaceable portions to an inoperative position with respect to the actuator.

21. Means as defined in claim 17 including means independent of the remainder of said system for driving said actuator.

22. Means as defined in claim 17 including a control panel having a slot therein corresponding to the path of travel of the actuator, the actuator being arranged to travel behind the panel, and a combined actuating and indicating handle connected to said actuator and extending through the slot and accessible from the front of the panel.

23. Means as defined in claim 17 including a substantially vertical panel at the control station having a slot therein corresponding to the path of travel of the actuator, the actuator being biased to move toward one extremity of the slot, means for moving the actuator in the opposite direction against the effort of the biasing means, and an indicator portion movable with the actuator and visible through the slot.

24. Means as defined in claim 23 wherein said indicator portion includes a handle projecting through the slot and accessible from the front of the panel and by which the actuator may be moved.

25. Means as defined in claim 17 including a master controller connected in series with said first-mentioned controllers, and an actuating portion for said master controller located near one extremity of the path of travel of the actuator and also actuatable by said actuator.

26. Means as defined in claim 17 wherein said controllers comprise diverting valves and said source of power comprises a source of fluid under pressure, time delay means interposed between said source and said controllers, a starting valve, an actuating portion for said starting valve located near one extremity of the path of movement of the actuator and operable in response to movement of the actuator to a starting position substantially at said extremity of its path of travel, and means responsive to operation of said starting valve for initiating action of said time delaying means.

27. In a sequence controlling system for a plurality of fluid-operable soot blowers including a controlled station appurtenant each such blower and a common control station for all of said controlled stations, means for connecting the control station to a source of control fluid under pressure, a fluid pressure operable driving motor for each blower appurtenant to each controlled station, means for connecting each such motor to a source of higher pressure motor driving fluid, diverting means at the control station for selectively directing the control fluid to predetermined controlled stations to regulate the action of the several blowers, said diverting means including a plurality of valving portions, a control conduit for connecting each such valving portion to one of the controlled stations, means including a cross-connecting valve at each controlled station operable by the appurtenant motor to effect a temporary cross connection between the higher pressure motor fluid supply source and the control line, and diverter actuating means at the control station connected to the control line and responsive to increased pressure therein to operate said valving portions.

28. A system as defined in claim 27 wherein

23

said valving portions are fixedly positioned and said diverter actuating means comprises a traveling actuator movable to sequentially operatively engage said valving portions, latch-type actuating abutment portions carried partly by said actuator and partly by said valving portions and interengageable to arrest the actuator during actuation of each valving portion, said diverter actuating means also including latch releasing means operable by such increased pressure in the control conduit to release said abutment portions from interengagement, travel of the actuator being arrested by and during such interengagement but permitted by such release.

29. Means as defined in claim 28 including driving means tending to move said actuator in one direction in which said abutment portions

24

may successively operatively interengage one another, said actuator being movable in an opposite direction during which movement said latch-type abutment portions may move past one another without such arresting interengagement.
